(57) CLAIM

The ornamental design for a gaming device, as shown and described.

DESCRIPTION

FIG. 1 is an exploded perspective view of a gaming device showing my new design, with the cover being removed from the top portion of a gaming device;

FIG. 2 is an exploded perspective view thereof, with the cover being removed from the bottom portion of a gaming device;
 FIG. 3 is a rear elevation view of the bottom portion of FIG. 1;

FIG. 4 is a front elevation view of FIG. 3;

FIG. 5 is a top plan view FIG. 3;

FIG. 6 is a left side elevation view of FIG. 3; and,

FIG. 7 is a right side view of FIG. 3.

The broken lines illustrate unclaimed portions and from no part of the claimed design.
